UNITED STATES PATENT OFFICE.

WILLIAM W. CAMERON, OF LA CROSSE, WISCONSIN, ASSIGNOR TO LA CROSSE PLOW CO., OF LA CROSSE, WISCONSIN, A CORPORATION OF WISCONSIN.

DOUBLE DISK HARROW.

1,223,145.

Specification of Letters Patent. Patented Apr. 17, 1917.

Application filed July 9, 1914. Serial No. 849,866.

To all whom it may concern:

Be it known that I, WILLIAM W. CAMERON, a resident of La Crosse, in the county of La Crosse and State of Wisconsin, have invented certain new and useful Improvements in Double Disk Harrows, of which the following is a full, clear, and exact description.

The invention relates to disk harrows and more particularly to that type which comprises plural members connected to travel in tandem relation, or one behind the other.

One object of the invention is to provide an improved harrow of this type in which all of the members are shiftable into and out of operative position by a common lever. Another object of the invention is to provide an improved harrow of this type in which a general frame to which all of the members are connected is dispensed with, the draft and shifting connections between the harrows serving to maintain them in proper relative position. A still further object of the invention is to provide a harrow of this type in which a frame and operating parts may be formed of wrought metal. Still further objects of the invention are to provide an improved construction of reach, an improved mounting for the shifting lever, brace-connections between the reach and the transverse draft-bar at the front of the machine, and improved draft-connections between the front and rear harrows. Other objects of the invention will appear from the detail description.

The invention consists in the several novel features of construction hereinafter set forth and more particularly defined by claims at the conclusion hereof.

In the drawings: Figure 1 is a plan of a harrow embodying the invention. Fig. 2 is a side elevation. Fig. 3 is a section taken on line 3—3 of Fig. 1. Fig. 4 is a perspective of the draft bar and its connections, the frames of the front harrow being also shown. Fig. 5 is a perspective of the rear harrow-frames and their connections. Fig. 6 is a rear-elevation of the adjustable stop for holding down the lever-operated draft links for the front harrow. Fig. 7 is a side elevation of the same.

The machine comprises a front harrow 10 composed of two members or sections 11, and a rear harrow 12 also composed of mem-

bers or sections 14. Each member of the front and rear harrows comprises a shaft 15, a gang of disks 16 scrapers 16^a and spacing spools 17 between the disks, all of which may be of usual construction, as well understood in the art.

A transversely extending draft-bar 18 is disposed forwardly of the front harrow and draft is applied thereto by means of links 19 and a clevis is usually connected by a chain to a tractor. Each link 19 has an eye 20 at its rear end which is connected to a loop 21 which is pivoted to one end of the cross bar 18 by a bolt 22.

A bearing 24 is mounted upon one of the spools 17 adjacent the inner end of each gang of the front harrow 10, and a bearing 25 is mounted at the side of each of said gangs on one of said spools. A standard 26 is secured to each bearing 24 and a standard 27 to each bearing 25, and an angle iron 28 connects the standards of each member 11 of the front harrow. Additional bearings 24^a and 25^a may, if desired, be secured to said cross-bars. These standards and cross-bars serve as frames for the members of the front harrow.

A longitudinally extending draft-connection is provided between each of the outer ends of the draft-bar 18 and the members of the front harrow respectively. Each of these connections comprises an upper bar or brace 34 and a lower bar or brace 30 which are secured at their front ends to the bar 18 by bolts 22. Each upper bar extends upwardly and rearwardly from bar 18 and is pivotally connected to one of the frame-bars 28 by a bolt 35 which passes through a strip 33 which is rigidly secured to bar 28. Each lower draft-bar or brace 30 extends downwardly and rearwardly from bar 18 and is pivotally connected by a bolt 31 to lugs 29 on bearing 25. Filler blocks 32 are placed inside of the angle-bar 18 for convenience in attachment of the parts thereto. Draft-braces 30 and 34 in extending downwardly and upwardly from the draft-bar 18 apply the power at a point substantially on a level with the bearings and at a point above the bearing to the frame-bar 28, thus forming a braced longitudinally extending draft-connection between the draft-bar 18 and the members of the front harrow respectively.

Pivot-bolts 35 and 31 are vertically alined

so that each harrow section may be adjusted horizontally to the desired angle to work the soil. Suitable bumpers 60 are placed on the inner ends of the front harrow-members, 5 the disks thereon being disposed to throw the soil outwardly. The inner end of each section of the front harrow is adjustably connected to the draft-bar by mechanism whereby the inner ends of the sections of 10 the front harrow may be shifted fore and aft and whereby said ends may be secured in fixed relation to the draft-bar. This mechanism comprises a hand-lever 36 which extends between the dual members or bars 37 15 of a reach 38 and is pivoted thereto by a bolt 39 which is disposed forwardly of the draft bar 18. The lower end of lever 36 is connected to each of the members of the front harrow by a connection comprising a link 40 pivoted to the lower end of lever 36 20 by a bolt 41 and having its rear end pivoted to the bearing 24 by a bolt 42.

A brace 43 is secured to each link 40 by a bolt 44 and extends upwardly and rearwardly and is pivotally connected by a bolt 47 to a strip 45 which is secured on one of the frame bars 28. These links and braces between the lever and the inner members of the front harrow form a substantial braced 30 draft connection for the inner ends of the members of the front harrow. A stop-plate 90 adjustably secured to bar 18 serves to hold down links 40 and the inner ends of the front harrow members.

35 Reach 38 is secured to the draft bar 18 by a standard formed of angular brackets 48 having their upper ends disposed between the members 37 of the reach, and a bolt 49 extending through the upper ends of said brackets and the reach-bars. The lower portions of brackets 48 are secured to draft-bar 18 by bolts 50. The front end of the reach is secured to each side of bar 18 by braces 51 and 52 extending forwardly and 45 inwardly from the top and front of the frame bar respectively. The front ends of these braces and the reach 38 are secured together by a bolt 52^a. This manner of construction provides a well-braced connection 50 between the reach and draft bar. A segmental rack 54 has legs 55 disposed between the reach-bars and is secured thereto by bolts 56 and 52^a. Spacing blocks 57 are held between the legs 55 of the rack bar and one 55 of the reach-bars 38 to space said members apart so that the lever 36 will be free to be shifted between said members. A lock bolt 58, operated by a finger-lever 59, is adapted to engage the notches in rack 54 to lock the 60 lever and its connections in desired positions. This manner of constructing the reach and disposing the angling lever and rack effectively supporting these parts.

When the lever 36 is shifted forwardly,

braces 43 and links 40 will be shifted rearwardly to cause the members of the front harrow to be angled horizontally, each section swinging about an axis formed by bolts 31, 35 thereon.

The rear harrow is connected to the shifting mechanism so that its members will be horizontally angled into forwardly convergent relation, oppositely with respect to the front members, which will be angled into rearwardly convergent relation, and lever 36 75 serves to conjointly shift the members of the front and rear harrows. Each rear member is provided with an outer bearing 63, an inner bearing 64, a standard 65 secured to bearing 63, a standard 66 secured to the bearing 64 and an angular cross bar 67 which is rigidly secured to the upper ends of the standards. Additional bearings 63' and 64' are secured to cross-bars 67. An angular plate or bar 68 is interposed between the inner ends of cross bars 67 and is connected to the inner ends of said bars respectively, by a bolt and slot connection 69. The disks of the rear members are faced to throw the soil inwardly when angled, and bar 68 90 serves particularly, when engaged by the reach-extension, to hold down the inner ends of the rear harrow-members, and also serves to support the reach-bar. These slot-connections permit the bar to accommodate itself to different positions as the rear gangs are angled.

Longitudinally extending draft connections are provided between the inner sides of the rear sections and of the front sections. 100 Each of these connections comprises a bar or link 70 which has its front end pivotally connected by a bolt 71 to the rear end of strip 33 which is fixed on front cross bar 28, and its rear end connected by a bolt 72 to a strip 73 secured on frame-bar 67. Each of these connections also comprises an arched bar 74 which has its central portion secured to bar 70 by bolts 75, its front end pivoted to a bearing 25 by a bolt 76, and its rear end pivoted to a bearing 63 by a bolt 77. These braces for these draft connections avoid the necessity of using direct links at the level of the bearings. Bolts 71, 76 are vertically aligned, and bolts 72, 77 are also aligned vertically so that the rear sections can swing horizontally. The connection for shifting and drawing the inner ends of the rear sections comprises a link 78, the front end of which is pivoted, as at 79, to the operating lever 36, and this reach extends between the reach-bars. The rear ends of bar 78 is connected by braces 80 to a yoke 81, the side arms of which have their rear ends pivotally connected to bearings 64, respectively, by bolts 82. The longitudinally extending draft-connections between the sides of the members are rearwardly divergent, as illus-

trated in Fig. 1. The disks of the members of the rear harrow have their inner faces concaved so that when they are in operative position the soil will exert an outward pressure upon these members. Resultantly, the divergent longitudinal draft-connections for the rear harrow exert in a degree an outward pull upon the front harrow members which have their disks faced so that they will be crowded together by the soil when in operation. By arranging the longitudinal connections to exert an outward pull upon the front members, the pressure between the bumpers 60 on the front members is lessened so as to overcome the grinding effect thereon.

When lever 36 is shifted forwardly to shift the links 40 rearwardly, bar 78 will be operated forwardly to angle the rear sections horizontally oppositely to the front sections.

A reach-extension or traction bar for applying draft to a seeder or other implement, which is to follow the harrow, consists of a pair of bars 84, the front ends of which are secured between the rear ends of the bars of reach 38, by bolts 85 and spacing washers 85'. The rear portions of the bars of reach-extension 84 are spaced apart, as at 86, to receive the front end of a traction bar extending to the implement to be drawn in the rear of the harrow. A loop 87 has its side arms secured to plate 68 by bolts 88 and its cross member overlies the reach to permit limited horizontal and vertical movement of the rear end of the reach.

The invention thus exemplifies a machine comprising front and rear harrows, each comprising a pair of pivoted members, and in which the front harrow-members may be operated into rearwardly convergent relation and the rear harrow members operated into forwardly convergent relation by a common lever which is pivoted in front of the front harrow. The invention also exemplifies a tandem harrow in which the longitudinal rearwardly divergent draft-connections are pivoted to the members. The angling lever and lock therefor are sustained by a braced structure in front of the draft-bar. The construction throughout is one which may be made of wrought metal and all of the parts are substantially constructed and well braced so that the implement is well adapted to be operated by a tractor.

The invention is not to be understood as restricted to the details set forth, since these may be modified within the scope of the appended claims without departing from the spirit and scope of the invention.

Having thus described the invention, what I claim as new and desire to secure by Letters Patent, is:

1. In tandem harrows, the combination of front and rear harrows, each comprising a

pair of members capable of being relatively angled, each member comprising a gang of disks, a draft-bar at the front of the front harrow draft-connections between the outer portions of said bar and the outer portions of the members of the front harrow, draft-connections at the sides of the harrow between the front and rear members, a lever for angling the members, and connections between said lever and all of the members for conjointly shifting the inner ends of the members of the front harrow into rearwardly converging relation and the members of the rear harrow into forwardly converging relation.

2. In tandem harrows, the combination of front and rear harrows, each comprising a pair of members capable of being relatively angled, each comprising a gang of disks, a draft-bar at the front of the front harrow, longitudinally extending draft-links between the sides of the front and rear members respectively, a lever for angling the members, and connections between said lever and the inner ends of all of the members for simultaneously angling the members of the front and rear harrows into convergent relation.

3. In tandem harrows, the combination of front and rear harrows, each comprising a pair of members capable of being relatively angled, each member comprising a gang of disks, a draft-bar at the front of the front harrow, draft-links between the outer ends of the draft-bar and the sides of the members of the front harrow, draft-links between the sides of the members of the front and rear harrows, a lever for angling the members, and link-connections between the lever and the inner ends of all the members for simultaneously shifting them into and out of angled positions.

4. In tandem harrows, the combination of front and rear harrows, each comprising a pair of members capable of being relatively angled, each member comprising a gang of disks, a draft-connection at the front of the front harrow, operatively connected to both of the harrows, a vertically swinging lever pivotally sustained in front of the front harrow members and extending rearwardly from its pivot to the rear of said front members, and connections between said lever and all of the members for shifting the members of the front harrow into a rearwardly converging position and the members of the rear harrow into forwardly converging position.

5. In tandem harrows, the combination of front and rear harrows, each comprising a pair of members capable of being relatively angled, each member comprising a gang of disks, a draft connection at the front of the front harrow, operatively connected to both of the harrows, a vertically swinging lever for angling the members pivotally sustained

- in front of the front harrow members and extending rearwardly from its pivot to the rear of said front members, link-connections pivoted to said lever and to the members of the front harrow, and oppositely working link-connections pivoted to said lever and to both of the members of the rear harrow, whereby all of the gangs will be simultaneously shifted by said lever.
6. In tandem harrows, the combination of front and rear harrows, each comprising a pair of members capable of being relatively angled, each member comprising a gang of disks, a draft bar at the front of the front harrow, draft connections between the outer ends of said bar and the outer portions of the members of the front harrow, draft connections for the rear harrow, a vertically swinging lever for angling the members pivotally sustained in front of the front harrow members and extending rearwardly from its pivot to the rear of said front members, and connections between said lever and all of the members for shifting the inner ends of the front members rearwardly into converging relation and the inner ends of the rear members into forwardly converging relation.
7. In tandem harrows, the combination of front and rear harrows, each comprising a pair of members capable of being relatively angled, each comprising a gang of disks, a draft bar at the front of the front harrow, longitudinally extending draft links between the sides of the front and rear members respectively, a vertically swinging lever for angling the members pivotally sustained in front of the front harrow members and extending rearwardly from its pivot to the rear of said front members and connections between said lever and the inner ends of all of the members for simultaneously angling the members of the front and rear harrows into convergent relation.
8. In tandem harrows, the combination of front and rear harrows, each comprising a pair of members capable of being relatively angled, each member comprising a gang of disks, a draft-bar at the front of the front harrow, draft links between the outer ends of the draft bar and the sides of the members of the front harrow, draft-links between the sides of the members of the front and rear harrows, a vertically swinging lever for angling the gangs pivotally sustained in front of the front harrow members and extending rearwardly from its pivot to the rear of said front members, and link-connections between the lever and the inner ends of all the members for simultaneously shifting them into and out of angled position.
9. In tandem harrows, the combination of front and rear harrows, each comprising a pair of members capable of being relatively angled, the members comprising a shaft, a gang of disks and a frame above the disks, each frame being capable of being angled relatively to the other, a draft-connection for the front harrow, draft-connections between the frames of the harrows, bearings on the shafts, longitudinal bars on the frames of the front harrow members, brace members secured to said latter draft connections and pivoted to said bearings and to said bars respectively, and mechanism for angling the gangs.
10. In tandem harrows, the combination of front and rear harrows, each comprising a pair of members capable of being relatively angled, each member comprising a shaft, a gang of disks and a frame above the disks, a draft-connection for the front harrow, draft-links pivoted to and extending between the frames of the harrows, bearings on the shafts, brace-members secured to said draft links and pivotally connected to said bearings, the pivotal connections between the links and the frames and the pivotal connections between the brace members and the bearings being coaxial, and mechanism for angling the frames.
11. In tandem harrows, the combination of front and rear harrows, each comprising a pair of members capable of being relatively angled, each member comprising a shaft carrying a gang of disks, draft-connections for the harrows, a lever for angling the members, and a connection with said lever for operating the members of one harrow comprising a yoke having its ends pivoted to the members of said latter harrow.
12. In tandem harrows, the combination of front and rear harrows, each comprising a pair of members capable of being relatively angled, each member comprising a shaft carrying a frame and a gang of disks, draft-connections for the harrows, a lever for angling the members, and a connection with said lever for operating the members of one harrow, comprising a link and a yoke secured to the link and having arms connected to the members of the latter harrow.
13. In tandem harrows, the combination of front and rear harrows, each comprising a pair of members capable of being relatively angled, each member comprising a shaft, a frame and a gang of disks, draft-connections for the harrows, a lever for angling the members, bearings on the shafts, and a connection between the lever and one of the harrows comprising a link and a yoke secured to the link and having its arms connected to the bearings of the members of one harrow.
14. In tandem harrows, the combination of front and rear harrows, each comprising a pair of members capable of being relatively angled, the members comprising a shaft, a gang of disks and a frame above the disks, each frame being capable of being angled relatively to the other, a draft-connection for the front harrow, draft-connections between the frames of the harrows, bearings on the shafts, longitudinal bars on the frames of the front harrow members, brace members secured to said latter draft connections and pivoted to said bearings and to said bars respectively, and mechanism for angling the gangs.

angled, each member comprising a shaft, a frame and a gang of disks, a draft-connection for the front harrow, a lever for angling the members, and a connection with 5 said lever for operating the members of the rear harrow comprising a yoke having its ends pivoted to the members of the rear harrow.

15. In tandem harrows, the combination 10 of front and rear harrows, each comprising a pair of members capable of being relatively angled, each member comprising a shaft, a frame and a gang of disks, a draft-connection for the front harrow, a lever for 15 angling the members, a connection with said lever for operating the members of the rear harrow, comprising a link and a yoke secured to the link and having arms connected to the members of the rear harrow.

20. 16. In tandem harrows, the combination of front and rear harrows, each comprising a pair of members capable of being relatively angled, each member comprising a shaft, a frame and a gang of disks, draft- 25 connections for the harrows, a lever for angling the members, bearings on the shafts, and a connection between the lever and the rear harrow comprising a link and a yoke secured to the link and having its 30 arms connected to the bearings of the members of the rear harrow.

17. In tandem harrows, the combination 35 of front and rear harrows, each comprising a pair of members capable of being relatively angled, each member comprising a gang of disks, draft-connections for the harrows, a lever for angling the members, a connection between the lever and the front members, and a connection with said 40 lever for operating the members of the rear harrow comprising a yoke having its ends pivoted to the members of said harrow.

18. In tandem harrows, the combination 45 of front and rear harrows, each comprising a pair of members capable of being relatively angled, each member comprising a gang of disks, draft-connections for the harrows, a lever for angling the members, a link connection between the lever and the 50 front members, and a connection with said lever for operating the members of the rear harrow, comprising a link and a yoke connected to the link and having arms connected to the members of the rear harrow, 55 respectively.

19. In tandem harrows, the combination 60 of front and rear harrows, each comprising a pair of members capable of being relatively angled, each member comprising a shaft, a frame and a gang of disks, draft-connections for the harrows, a lever for angling the members, bearings on the shafts, links connecting said lever and bearing on the front members, and a connec-

tion between the lever and the rear harrow 65 comprising a link and a yoke connected to the link and having its arms connected to the bearings of the members of the rear harrow.

20. In tandem harrows, the combination 70 of front and rear harrows, each comprising a pair of members capable of being relatively angled, each member comprising a shaft, a gang of disks on the shaft and a frame above the disks, bearings on the 75 shafts, draft-connections for the harrows, a lever, and connections for angling the harrows, the angling connections for one harrow comprising links connected to the lever and braces, the links and braces being 80 pivoted to the bearings and frames, respectively.

21. In tandem harrows, the combination 85 of front and rear harrows, each comprising a pair of members capable of being relatively angled, each member comprising a shaft, a gang of disks on the shaft and a frame above the disks, bearings on the shafts, draft-connections for the harrows, a lever and connections for angling the harrows, the angling connections for one harrow comprising links pivoted to the lever 90 and the bearings and braces pivoted to the frames and secured to the links.

22. In tandem harrows, the combination 95 of front and rear harrows, each comprising a pair of members capable of being relatively angled, each member comprising a shaft, a gang of disks and a frame above the disks, mechanism for shifting the members of the harrows into convergent position, 100 draft-connections for the harrows, and a connecting bar between the inner ends of the frames of one of the harrows, and bolt-and-slot connections between the bar and 105 said latter frames.

23. In tandem harrows, the combination 110 of front and rear harrows, each comprising a pair of members capable of being relatively angled, each member comprising a shaft, a gang of disks and a frame above 115 the disks, mechanism for shifting the members of the harrows into convergent position, draft-connections for the harrows, a bar between and connected to the inner ends of the frames of one of the harrows, and a draft-reach extending over and supported by said bar.

24. In tandem harrows, the combination 120 of front and rear harrows, each comprising a pair of members capable of being relatively angled, each member comprising a gang of disks and a frame above the disks, mechanism for shifting the members of the harrows into convergent position, draft-connections for both harrows, and a bar between the inner ends of the frames of one 125 of the harrows, bolt-and-slot connections be-

tween the bar and said latter frames, and a draft-reach extending over said bar.

25. In tandem harrows, the combination of front and rear harrows, each comprising

- 5 a pair of members capable of being relatively angled, each member comprising a gang of disks and a frame above the disks, a transversely extending draft-bar in front of the front harrow, draft-connections between the ends of the transverse bar and the sides of the members, a reach rigidly secured to and extended forwardly of said transverse-bar, and a lever pivotally connected to the front of the reach for angling 15 the members.

26. In tandem harrows, the combination of front and rear harrows, each comprising a pair of members capable of being relatively angled, each member comprising a gang of disks, a transversely extending draft-bar in front of the front harrow, draft-connections between the ends of the transverse-bar and the sides of the members, a standard secured to the transverse draft-bar, a reach secured to said standard and an angling lever on the reach.

27. In tandem harrows, the combination of front and rear harrows, each comprising a pair of disk gangs capable of being relatively angled, a transversely extending draft-bar in front of the front harrow, longitudinally extending draft connections between the outer ends of the transverse-bar and the front gangs, a reach secured to said transverse bar and extending forwardly thereof, a standard between the reach and the transverse bar, and braces between the front end of the reach and the transverse bar.

- 40 28. In tandem harrows, the combination of front and rear harrows, each comprising a pair of members capable of being relatively angled, each member comprising a gang of disks, a transverse bar in front of the front harrow, longitudinally extending draft-connections between the outer ends of the transverse bar and the front members, a reach on the transverse bar comprising a pair of bars spaced apart, an angling lever pivoted between said reach bars, and an angling connection operated by said lever.

29. In tandem harrows, the combination of front and rear harrows, each comprising a pair of members capable of being relatively angled, each member comprising a gang of disks, a transversely extending draft-bar in front of the front harrow, longitudinally extending draft-bars between the outer ends of the transverse bar and the front members, a reach, comprising spaced bars secured to the draft-bar, said bars extending rearwardly over the rear harrow, and mechanism for angling the members.

- 65 30. In tandem harrows, the combination

of front and rear harrows, each comprising 65 a pair of members capable of being relatively angled, each member comprising a gang of disks, draft means for the front harrow, longitudinally extending rearwardly divergent draft bars for the rear harrow 70 having their front ends connected to receive draft and having their rear ends pivotally connected to the outer sides of the rear harrow members respectively, the inner portions of the rear harrow members being movable fore and aft around the pivotal connections to said draft bars, and means for angling the members.

31. In tandem harrows, the combination of front and rear harrows, each comprising 80 a pair of members capable of being relatively angled, each member comprising a gang of disks, draft-means for the front harrow, draft-connections between the harrows, a reach connected to the draft means 85 for the front harrow and extended rearwardly over the rear harrow and means on the harrow for limiting the movement of the reach.

32. In tandem harrows, the combination 90 of front and rear harrows, each comprising a pair of members capable of being relatively angled, each member comprising a gang of disks, a transversely extending 95 draft bar in front of the front harrow, longitudinally extending draft bars between the outer ends of the transverse bar and the front members, a reach secured to the draft-bar and extended rearwardly over the frame of the rear harrow, and a loop on the rear 100 harrow overlying the rear portion of said reach.

33. In tandem harrows, the combination of front and rear harrows, each comprising 105 a pair of members capable of being relatively angled, each member comprising a gang of disks, a transversely extending draft-bar in front of the front harrow, longitudinally extending draft-bars between the outer ends of the transverse bar and the 110 front members, a reach secured to the draft-bar and extended rearwardly over the frame of the rear harrow, a bar connecting the inner ends of the members of the rear harrow, and a loop overlying the rear portion 115 of said reach and secured to said connecting-bar.

34. In tandem harrows, the combination of front and rear harrows, each comprising 120 a pair of members capable of being relatively angled, each member comprising a gang of disks, a transversely extending bar in front of the front harrow, a reach secured to said bar comprising a pair of bars spaced apart, a lever pivoted to said reach and a link connection with one of said 125 harrows operated by said lever and extending between said reach-bars.

35. In tandem harrows, the combination of front and rear harrows, each comprising a pair of members capable of being relatively angled, each member comprising a gang of disks, a transversely extending bar in front of the front harrow, a reach secured to said bar comprising a pair of bars spaced apart, a lever pivoted between said reach-bars and a link connection with one of said harrows operated by said lever and 10 extending between said reach-bars.
